METHOD OF MAKING CEMENT

Walter Dyckerhoff, Mainz-Amoeneburg,
GermanyOriginal application November 23, 1935, Serial
No. 51,331. Divided and this application Octo-
ber 6, 1936, Serial No. 104,263

2 Claims. (Cl. 263—53)

This application is a division from application Serial No. 51,331, filed November 23, 1935.

The present invention relates to the production of cement by feeding a cement slurry to the rotary kilns customarily used in this art through atomizing nozzles, wherein the slurry is dispersed in sheets within the drying zone of the kiln to bring the slurry particles and nodules into intimate contact with the heating stream for positively and completely contacting the atomized materials and effecting a complete desiccation thereof with a minimum fuel consumption.

In cement burning operations carried through in the manner hereinbefore described the cement slurry has been forced under pressure into the kiln through a nozzle, wherein the slurry was spread out in a sheet so that the hot gases passing through the latter could completely permeate the slurry.

20 The present improvement is designed to render the cement burning process more economical and to this purpose I feed the slurry under pressure through a single conduit to a plurality of nozzles, each nozzle extending into the drying zone of a separate rotary kiln to spread the slurry in this kiln into a uniform sheet.

In order that this can be done on a commercial scale, care must be taken to protect the nozzles against a speedy destruction by the frictional wear exerted on the mouthpieces of the nozzle by the hard solid particles in the slurry which are forcibly brought into contact with the nozzle borings.

Obviously, if such wear of the nozzle mouthpieces were not prevented from occurring, the several nozzles would be worn down to a different extent and consequently a larger quantity of slurry would be fed per unit of time to one or part of the kilns.

40 I avoid these difficulties by ejecting the slurry into the kilns through nozzles of practically invariable diameter and by apportioning to each of the kilns the quantity of slurry corresponding to the dimensions of each individual kiln by ejecting the slurry through nozzles of corresponding dimensions.

To this end each nozzle is fitted out with a mouthpiece selected for each individual kiln as far as its boring is concerned and I form these mouthpieces with inserts of a material of high resistivity to wear. In this manner I am enabled to supply cement slurry to a number of kilns through a single conduit and with the aid of a single pump without being required to con-

tinuously exchange worn nozzles in order to keep the supply to each kiln constant.

In the drawing affixed to this specification and forming part thereof,

Fig. 1 is a side elevational view of a slurry supply pipe and nozzle head constructed in accordance with the present invention, illustrating the manner of mounting the head in a kiln.

Fig. 2 is a sectional view taken on the line 2—2 of Fig. 1 looking in the direction of the arrows, showing the outlet end of the spray head nozzles.

Fig. 3 is a detail fragmentary longitudinal sectional view taken through one of the nozzles.

Fig. 4 is a sectional view taken on the line 4—4 of Fig. 3 looking in the direction of the arrows, illustrating the manner of mounting the spiral shaft or core in the nozzle casing, and

Fig. 5 is a perspective view of the spiral shaft or core showing to advantage the overlapping of the terminals of the vanes.

Referring to the drawing, each of the nozzles, as illustrated to advantage in Fig. 1, includes a cylindrical casing 13, the outer end of the bore of which is enlarged to provide an annular shoulder 14 adapted to be engaged by the inner ends 25

of vanes 15, which latter form an integral part of a nozzle core 16. The vanes 15 are formed spirally on the periphery of the core shaft, the outer end of which latter issues into a conical terminal 17. It will be noted upon reference to Fig. 5 of the drawing that in the present instance, I employ three vanes, the end of each of which overlaps an end of the two remaining vanes, and is bevelled to provide an edge 18.

Each vane extends through an angle of less than 360° and preferably less than 180° in order not to unduly increase the constriction and the consequent velocity of flow of the jet of slurry.

The outer ends of the vanes 15 engage the inner wall of a cup or mouthpiece 19, the latter being concentrically mounted in the enlarged bore of the casing 13 and projecting beyond the latter as shown in Fig. 5. The inner wall of the mouthpiece is dished out to provide an acutely tapering trumpet-like wall 20, the entrance portion of which encloses with the inner wall of the

casing an angle ranging between 90° and 135°, and which terminates in a central opening formed in the mouthpiece in which opening I mount a nozzle tip or insert 21, made of spe-

cial wear resisting material. The tip is provided with a central bore, the inner end of which flares outwardly so as to coincide with and form a continuous part of the wall 20. It will be noted from Fig. 1 that the tapering terminal 55

or nose 17 of the core is centered in the mouthpiece 19 but spaced from the wall of the latter and from the bore of the tip 21 at all points around its periphery. The core 16 and mouthpiece 19 are secured from movement or displacement by a cap 22, the latter being detachably mounted on the casing 13 and provided with a central opening 23, the diameter of which approximately corresponds to the diameter of the tip 21.

Following the teaching of the present invention, the slurry is fed under pressure by a pump (not shown) through the supply pipe 8, branches 9, and discharge pipe 11 into the head 12. In 15 the head 12 the slurry is divided for discharge through the nozzles 13. A column of slurry passing through the casing 13 of a nozzle impinges on the inner ends of the vanes 15, at which point the column is subdivided and contact had with the acutely tapered wall 20 of the mouthpiece 19. Since the slurry is passing through the nozzle under pressure a whirling action results, which action is accelerated by the construction of the wall of the mouthpiece 19 and the configuration of the terminal 17. The maximum velocity of the slurry is at the point of discharge of the latter outside of the discharge end of the nozzle. By reason of the whirling action the slurry, immediately after leaving the nozzle, is 20 dispersed and forms a sheet with the nozzle substantially at the center thereof and extending in a direction generally transverse of the kiln. The heating gases moving longitudinally in the kiln impinge on the sheet of slurry. Since the tip 21 25 is made of wear resisting material, the bore of the tip remains constant, thereby preventing variation in the volume of slurry passing through the tip. Moreover, instead of replacing the nozzle after a very short period of use, sometimes 30 only a few hours, as is now customary when nozzles are used, the nozzle of the present invention may be used for approximately a year under ordinary conditions.

By use of the nozzle above described it is possible to obtain an automatic apportionment of the slurry fed to each kiln where a battery or series of kilns of the same size or of different sizes are used supplied by a single pump. In this 5 operation the slurry is pumped to the various kilns through the slurry supply pipes and discharged through the nozzles of the present invention, the apportionment of the slurry being adjusted by the size of the outlet openings of the 10 nozzles. It is, of course, understood that the mouthpieces of the nozzles are provided with openings varying in diameter, each mouthpiece being detachable to permit its replacement by a mouthpiece having an opening of a different 15 diameter where the apportionment of the slurry is to be changed.

While I have herein described a preferred form of my invention, it is nevertheless to be understood that various changes may be made therein 20 within the scope of the claims herewith appended.

I claim:—

1. In the manufacture of cement by injecting into a rotary kiln through a nozzle cement slurry under pressure in combination, the steps of sub- 25 dividing the slurry into a plurality of currents, ejecting each current into a separate kiln through a nozzle dimensioned in proportion to the capacity of each kiln and spreading the cement slurry ejected through said nozzle into a thin substan- 30 tially uniform sheet and in a generally transverse direction of the kiln and impinging heating gases on said sheet.

2. In the manufacture of cement the steps of injecting into a rotary kiln a cement slurry under 35 pressure and spreading the slurry into a thin substantially uniform sheet extending in a generally transverse direction with respect to the kiln and directing a current of heating gases longitudinally of the kiln into impingement on 40 said sheet.

WALTER DYCKERHOFF.
